BELT

Filed April 24, 1930

UNITED STATES PATENT OFFICE

ROBERT H. GLECKNER, OF CANTON, PENNSYLVANIA

BELT

Application filed April 24, 1930. Serial No. 447,005.

The invention relates to a flexible link garment supporting belt, and it aims to provide a novel article which is improved from standpoints of utility, strength, appearance, 5 comfort, health and economy.

With the foregoing in view, the invention resides in the novel subject matter herein-after described and claimed, description being accomplished by reference to the accompanying drawing.

Fig. 1 is a front elevation of a belt constructed in accordance with my invention.

Fig. 2 is a detail horizontal sectional view on line 2—2 of Fig. 1.

Fig. 3 is a detail horizontal section as indicated by line 3—3 of Fig. 1.

Fig. 4 is a view similar to Fig. 3 but illustrating the belt reversed with respect to the buckle.

Fig. 5 is a perspective view of one of the flexible links.

The belt embodies a plurality of flexible links 6, one end link 6^a and another end link 6^b. One end of each of the links 6 and 6^a is formed with a single transverse slit 7, while the opposite end of each of these links is formed with a pair of transverse slits 8 and 9. Each link is of U-shape in edge view and the bight portion 10 of any link 6 or 6^b passes through the opposed slits 7 and 9 of the next adjacent link. The bight portion 10^a of the link 6^a passes through a slot 11 in one end 12 of a buckle-attaching strap 13. This strap is detachably engaged with either a cam buckle or a tongue buckle 14, and separable fasteners 15 and 16 are provided for securing said strap. One of the fasteners 15 passes through the strap end portion 12, both fasteners 16 pass through the opposite end portion 40 of the strap 13, and the other fastener 15 passes through the link 6^a.

The link 6^b at the opposite end of the belt, is somewhat different from the other links, being provided only with two slots 8^a and 9^a. One end 17 of a buckle-engaging strap 18, is secured between the ends of this link 6^b, by stitching or the like 19.

Interlaced with the slots 8 and 9 and 8^a and 9^a, is a flexible inlay strip 20 which is disposed totally at one side of the belt, as seen in Figs.

1, 2 and 3. One end 21 of this strip 20 passes inwardly through the slot 11 and is fastened against the inner side of the strap end 12 by one of the fasteners 15, as seen in Fig. 3. The adjacent portion of the strip 20 is also secured to the link 6^a by the other of the fasteners 15. At the opposite end of the belt, the end 22 of the inlay strip 20 extends along the buckle-engaging strap 18 and is secured to the latter by stitching 23.

Material of adequate tensile strength is used for the inlay strip 20 so that it will decrease the amount of stretch to an extent far below that customary with flexible link belts, and as said strip 20 is totally at one side of the belt instead of zig-zagging from side to side of the latter, it is better suited to minimize the stretch in the belt. Another advantage for having the strip 20 at only one side of the belt, is that it virtually provides two belts in one, in that the belt may be worn one side out with one appearance and the other side out with a distinctly different appearance. In order to thus reverse the belt it is only necessary to release the fasteners 16, reverse the buckle 14 and reverse the keeper 24 for the free end of the belt, as illustrated in Fig. 4.

The novel construction herein described is advantageous over conventional flexible link belts, in that it reduces the extreme elasticity, thus giving more ideal support to the trousers, increases strength, as numerous leathers used for link belts do not possess sufficient tensile strength to prevent excessive stretching or tearing, is flexible and elastic to the proper degree, very light and cool, comfortable to the maximum and thus ideal for health, etc. When the belt is used by golf players, the inlay strip 20 serves as an effective holder for a plurality of tees and when they are removed, the belt immediately resumes its former attractive appearance. The appearance of any belt may be changed by reversing it as above explained, and in the manufacture of the belts, different effects may be obtained by combining materials of harmonizing or contrasting colors, the various links for instance being one color and the inlay strip another color.

I claim:—

1. In a belt, a plurality of flexible links each of U-shape in edge view, one end of each link having a single transverse slit and the other end of each link being provided with a pair of transverse slits, the bight portion of each link being passed through said single slit and one of said pair of slits of an adjacent link, and a flat flexible strip extending longitudinally at one side only of the belt, said strip being interlaced with said pair of slits of each link.

2. In a belt, a plurality of flexible links each of U-shape in edge view, one end of each link having a single transverse slit and the other end of each link being provided with a pair of transverse slits, the bight portion of each link being passed through said single slit and one of said pair of slits of an adjacent link, a flat flexible strip extending longitudinally at one side only of the belt, said strip being interlaced with said pair of slits of each link, a buckle-attaching strap of U-shape in edge view, one end of said strap having a slot through which the bight portion of the link at one end of the belt passes, one end of the aforesaid strip being passed inwardly through said slot, and separable fasteners for securing said strap ends together, one of said fasteners securing said strap end and said one end of said strip together; and a buckle-engaging strap having one end secured between the ends of the link at the other end of the belt, the other end of said strip being extended along and secured to one side of said buckle-engaging strap.

3. In a belt, a plurality of flexible links each of U-shape in edge view, one end of each link having a single transverse slit and the other end of each link being provided with a pair of transverse slits, the bight portion of each link being passed through said single slit and one of said pair of slits of an adjacent link, a flat flexible strip extending longitudinally at one side only of the belt, said strip being interlaced with said pair of slits of each link, a buckle-attaching strap of U-shape in edge view, one end of said strap having a transverse slot through which the bight portion of the adjacent endmost link passes, one end of said strip being passed also through said slot, and separable fasteners for securing the two ends of said strap together, one of said fasteners passing through said strip end and through said one end of said strap to secure them together.

4. In a belt, a plurality of flexible links each of U-shape in edge view, one end of each link having a single transverse slit and the other end of each link being provided with a pair of transverse slits, the bight portion of each link being passed through said single slit and one of said pair of slits of an adjacent link, a flat flexible strip extending longitudinally at one side only of the belt, said

strip being interlaced with said pair of slits of each link, and a buckle-engaging strap having one end secured between the ends of the adjacent endmost link, one end of said strip being extended along one side of said strap and secured thereto.

In testimony whereof I affix my signature.

ROBERT H. GLECKNER.
